[57] CLAIM

The ornamental design for a corner table, substantially as shown and described.

DESCRIPTION

FIG. 1 is a side elevational view of a corner table showing my design;

FIG. 2 is an end elevational view; and

FIG. 3 is a top plan view thereof.

The side and end of the table not shown are like the respective side and end shown in FIGS. 1 and 2.

FIG. 1

FIG. 3
